Primary Examiner — Jonathan J Han*Assistant Examiner* — Christen Pilar Brown(57) **CLAIM**

The ornamental design for a slipper, as shown and described.

DESCRIPTION

FIG. 1 is a front, left and top perspective view of a slipper showing my new design.

FIG. 2 is a rear, right and bottom perspective view thereof.

FIG. 3 is a rear and top perspective thereof.

FIG. 4 is a left view thereof.

FIG. 5 is a right view thereof.

FIG. 6 is a front view thereof.

FIG. 7 is a rear view thereof.

FIG. 8 is a top view thereof; and,

FIG. 9 is a bottom view thereof.

The broken lines shown in the drawings are included for the purpose of illustrating portions of the slipper that form no part of the claimed design.

1 Claim, 9 Drawing Sheets(56)
